UNITED STATES PATENT OFFICE

MAGNUS E. WIDELL, OF CINCINNATI, OHIO, ASSIGNOR TO AMERICAN CAN COMPANY, OF NEW YORK, N. Y., A CORPORATION OF NEW JERSEY

INTERIOR-COLLAR CAN

Application filed January 26, 1924. Serial No. 688,641.

My present invention relates to side tearing strip cans provided with an interior collar extending above the tearing strip to prevent spilling of the contents when the tearing strip 5 is removed and to provide a shoulder adapted to receive the severed cover as a slip closure after the container has been opened.

A principal object of the invention is the provision of an improved construction of the 10 collar band in such a container adapted to produce a particularly tight and effective joint between the ends of said band.

Numerous other objects and advantages of the invention will be apparent as it is better 15 understood from the following description, which, taken in connection with the accompanying drawings, discloses a preferred embodiment thereof.

Referring to the drawings, 20 Figure 1 is an elevational view, partially broken away and shown in section, of a container in which my invention is embodied; Fig. 2 is a top plan view of the collar band; Fig. 3 is an enlarged section, taken substantially on the line 3—3 in Fig. 2; and Fig. 4 is a similar section taken on the line 4—4 in Fig. 2.

The container as thus illustrated comprises a body 21, having permanently secured top 30 and bottom ends 22 and 23 and being formed with the usual side seam 24. A side tearing strip, indicated at 25, is set off by circumferential score lines 26 and 27 and is provided with diagonal scores 28 adapted to direct the 35 line of tear back to the circumferential lines in case it should be deflected therefrom. A tongue 30 is provided at the end of the tearing strip for engagement by a key for removal of said strip.

40 A collar band 29 is secured to the body of the container below the tearing strip by means of an interfitting bead 31 and extends above said tearing strip, having its upper edge disposed near the top of the container.

45 The ends of said band are slotted, as indicated at 32 and 33, and are interlocked, as shown in Figs. 1 and 3. The sections of the 50 ends between said slits 32 and 33 are welded together at points indicated by the reference characters 34, 35 and 36. A very tight joint

is thus formed, resulting in a substantially continuous member fitting snugly within the container body.

For the purposes of the best economical, rapid and successful production by automatic 55 machinery these collars must be made, and maintained until they are accurately inserted in the cans, of exact diameter and of uniform width (vertical dimension) all around the perimeter of the collar, without projecting 60 corners, and by my improvement these desirable and new results are obtained, so that by the use of my invention much expense is saved in the manufacture of the cans.

It is thought that the invention and many 65 of its attendant advantages will be understood from the foregoing description, and it will be apparent that various changes may be made in the form, construction and arrangement of the parts without departing 70 from the spirit and scope of the invention, or sacrificing all of its material advantages, the form hereinbefore described being merely a preferred embodiment thereof.

I claim: 75

1. A container, comprising a body scored circumferentially to provide a side tearing strip, a top secured to said body, and a collar secured to the body beneath said tearing strip and extending thereabove, said collar having its ends overlapped and welded together to form a continuous member fitting snugly within the body of the container, the body being one piece of metal extending down past and below said collar.

2. A container, comprising a body scored circumferentially to provide a side tearing strip, a top secured to said body, and a collar secured to the body beneath said tearing strip and extending thereabove, said collar having its ends interlocked and welded together to form a continuous member fitting snugly within the body of the container, the body being one piece of metal extending down past and below said collar.

3. A container, comprising a body scored circumferentially to provide a side tearing strip, a top secured to said body, and a collar secured to the body beneath said tearing strip and extending thereabove, said collar 100

having its end slitted and interengaged and having the individual sections between the slits welded together to form a continuous member fitting snugly within the body of the container, the body being one piece of metal extending down past and below said collar.

MAGNUS E. WIDELL.
